UNITED STATES PATENT OFFICE

157,449

BUILDING STRUCTURE

George D. Tesch, Chicago, Ill.

Application May 9, 1947, Serial No. 138,959

Term of patent 14 years

(Cl. D13—1)

To all whom it may concern:

Be it known that I, George D. Tesch, a citizen of the United States of America and resident of the city of Chicago, county of Cook, and State of Illinois, have invented a new, original, and ornamental Design for a Building Structure, of which the following is a specification, reference being had to the accompanying drawing, forming a part thereof.

In the drawing—

Figure 1 is a front elevational view of the building structure showing my new design.

Fig. 2 is a top plan view with a portion of the building broken away for convenience of illustration.

Fig. 3 is a horizontal sectional view with a portion of the building broken away for convenience of illustration.

Fig. 4 is a vertical section in the plane of line 4—4 on Figs. 2 and 3.

I claim:

The ornamental design for a building structure, substantially as shown.

GEORGE D. TESCH.
